FILING DEVICE

William Evans Camp, Abington, Pa.

Application May 1, 1933, Serial No. 668,711

4 Claims. (Cl. 129—16)

This invention relates to filing systems or devices and, more particularly to receptacles, such as drawers or trays, for the retention of cards arranged in consecutive relation, alphabetically, numerically, or similar predetermined sequence; said cards bearing reference data—or other informative matter—which may be inspected, or a particular card elevated or removed at will, for posting purposes and so forth.

10 The primary object of my invention is to so shape or corrugate the surface on which the filing cards rest as to provide an alternating series of high and low positions, so that the leading card at each high point will have its top margin exposed above the top edges of the cards immediately in advance of it, whereby the filing indicia, or other informative data endorsed across the top of said high card may be visible from the front of the drawer or tray.

15 Another object is to provide a self indexing card file in which the top margins of cards at intervals from front to back of the retaining receptacle automatically elevate themselves and become visible above the balance of the cards in the complete series.

20 A further object is to so shape the surface on which the cards rest so as to provide a gradual slope, from each high card having its upper margin exposed, toward the rear or next high card, whereby the tops of the cards on said slope are supported in "fanned" relation and are thereby more easily fingered for selection or removal.

25 Ancillary objects, as well as a full comprehension of the advantages of my invention, will be apparent to those acquainted with the art upon a perusal of the following description and subjoined claims in conjunction with the accompanying drawings; and on which like reference symbols indicate corresponding parts in all the views.

30 In the drawings:

35 Fig. 1 is a perspective view of a card-filing drawer embodying the present improvements, as viewed from a frontal angle, and with portions broken away to better disclose otherwise hidden features.

40 Fig. 2 is a similar perspective view looking from the rear toward the front of the drawer.

45 Fig. 3 is a perspective view, corresponding to Fig. 2, of a filing tray embodying the instant invention.

50 Fig. 4 is a fragmentary longitudinal sectional view through Fig. 1.

55 Figs. 5 to 7 inclusive are, respectively, fragmentary illustrations of further forms of the in-

vention, and later on individually more fully described.

Referring first to Figs. 1 and 2, a conventional form of standard filing-cabinet or desk drawer is comprehensively designated by the symbol "D"; the same embodying front and rear walls 1, 2, side walls 3, a bottom 4, and a follower 5, in accordance with known practice in the art.

In adapting the drawer "D" to my improvements, I form or furnish in the bottom 4, inside of said drawer, paralleling corrugations or attached elements 6, each of the latter being suitably fashioned to provide a succession of transversely-aligned ridges or abutments 7, defining rearwardly-declining card-support 8, with intervening "flats" or horizontal portions 9. Preferably, although not essentially, the elements 6 are made from sheet metal with the ridge abutments 7 in consecutive equally-spaced relation; while the card-supporting sections 8, may have the upper surface wholly, or in part suitably roughened, as indicated at 10 in Figs. 1 and 2. These transverse corrugations or ridge abutments 7 tend to prevent the last card on the sloping surface 8 from sliding down; while the roughing 10 is to prevent the cards from sliding down towards or against the rearwardly-considered abutment 7, thereby decreasing pressure against said abutment. Provision of the "flats" 9 also serves a similar purpose by allowing the rearmost card supported on each surface 8, 9 to drop and reveal the card on the next succeeding ridge 7.

Each series of cards, bearing frontal name data "d" and serial numberings "n" across the upper margins, are designated by the symbol 11, and it will be readily understood that when the space intervening consecutive abutments 7 is substantially packed, that said cards are retained in approximately vertical position, as shown. Furthermore it will be also noted that the individual cards 11 are supported on the sections 8 in downwardly-declined individual relation. Now it will be obvious that as each set of cards 11 is manipulated by the forefinger, as indicated in dot-and-dash lines in Fig. 4, that the inclined supporting-section 8 therebelow "fans" the top edges of said cards and thereby renders it easier to finger them, consecutively.

Still further, it will be readily understood that by the act of what is commonly termed "thumbing" the cards that the card or cards "fanned" or, being inspected, are rearwardly projected at the lower edges against the proximate abutment 7 with incidental retention of the succeeding set in proper position without the leading card or

cards thereof slipping down into the forward flat 9.

In Figure 3 I have shown my improvements as applied to a filing tray "T", of conventional formation, having supporting legs or feet 12, said tray being equipped with transverse corrugations or parallel strip elements 6, and a follower 5, as above set forth. Accordingly corresponding reference symbols are applied in order to avoid repetitive explanation.

In Fig. 5 the element 6 is shown with a convexed card supporting section 16, and in Fig. 6 said section is concaved, as at 16'; both of said formations materially aiding "fanning" of the cards.

In Fig. 7 I have illustrated a still further formation for the corrugated element or elements 6, wherein the abutments 7 are of somewhat greater height, and are retroverted; for example, to provide ridge-stops 17 at the upper forward edges of the card supporting sections 8. Obviously, these stops 17 may be otherwise formed and are designed to preclude the leading card of each division from falling forwardly into the preceding division and becoming damaged incident to frequent usage or removal.

Incidentally it is to be remarked that the card supporting surfaces or elements 6 may be generally described as "saw-toothed" shaped corrugations with the steep or vertical edges towards the front of the drawer "D" or tray "T" and the less steep or sloping edges declined toward the rear thereof. Further it is noteworthy that when the cards are placed in a drawer or tray, embodying my improvements, they may be considered as automatically separating themselves into consecutive sections or sets with the leading card of each such section or set in the highest position with its upper margin exposed, and the last card of the same section or set immediately in front of the first card of the succeeding set, but in a depressed position so as not to obscure the informative upper margin of the said first card of such succeeding set.

From the foregoing it is thought the merits and

advantages of my invention will be fully appreciated, while it is self-evident that the card separating elements 6 may be formed as inserts for filing receptacles, as attachments therein, or as integral parts of the receptacle bottom 4. Furthermore while the described structures are particularly well adapted for drawers and trays, the same may be applied to various other services where it is desirable that the upper portions of consecutive elements be readily exposed for reference and so forth; while I entirely eliminate the necessity of providing the cards with data tongues or tabs that are so readily damaged or broken off. Accordingly I do not desire to be restricted to the precise structural embodiments illustrated and described, other than as limited by the terms of the subjoined claims.

Having thus described my invention what I claim is:—

1. As a new article of manufacture an insert for filing receptacles consisting of sheet metal corrugated to provide substantially vertical surfaces with intervening inclined card-supporting areas and lower narrow flats.

2. As a new article of manufacture an insert for filing receptacles corrugated to provide substantially vertical walls with intervening arcuate card-supporting areas.

3. As a new article of manufacture an insert for filing receptacles corrugated to provide substantially vertical walls with intervening arcuate card-supporting areas and lower narrow flats.

4. A filing device for cards comprising a receptacle adapted to receive cards, and means for supporting cards in the receptacle in groups consisting of a strip of sheet material extending longitudinally of the receptacle and crimped transversely to form upstanding ridges each having a vertically disposed front face and a downwardly sloping rear face spaced from the front face of an adjacent ridge to provide a flat horizontally extending face between said vertical and sloping faces.
